UNITED STATES PATENT OFFICE.

THOMAS J. McCONNAUGHAY, OF WARRENSBURG, MISSOURI.

PORTABLE BATHING-MACHINE.

SPECIFICATION forming part of Letters Patent No. 259,568, dated June 13, 1882.

Application filed March 10, 1882. (No model.)

To all whom it may concern:

Be it known that I, THOMAS J. McCONNAUGHAY, a citizen of the United States, residing at Warrensburg, in the county of Johnson and State of Missouri, have invented certain new and useful Improvements in Portable Bathing-Machines, of which the following is a specification, reference being had therein to the accompanying drawings.

10 My invention relates to portable shower-baths; and it consists in the construction and arrangement of its several parts, as will be more fully set forth hereinafter, and also pointed out in the claims.

15 In the drawings, Figure 1 is a side elevation, and Fig. 2 is a vertical section.

A represents the reservoir or receptacle for the water, and is preferably made in the form of a narrow cylinder, which is journaled centrally between the arms of the bail *a*, and is adapted to revolve thereon. It is provided with a nozzle, *a'*, situated upon the circumference of the cylinder, and into which is driven or screwed, as may be desired, a plug, *b*.

25 Through the center of this plug passes a flexible pipe, *b'*, to the free end of which is attached the sprinkler *b*², as shown. This pipe may be of any length desired. By the use of this flexible pipe the reservoir need not be hung immediately over the person who is to receive the bath, but may be hung against the wall or to any convenient support and the water conveyed to its destination through the pipe *b'*.

30 Extending around the circumference of the cylinder, from the opposite side to the nozzle, is a vent-pipe, *c*, which communicates with the interior of the cylinder, and the air, as shown. *d d* are supports attached to the circumference of the cylinder, and upon which the device rests when not in operation, as shown in Fig. 1.

35 Situated within the cylinder, a short distance to the left of the opening of the vent-pipe *c*, is a balance-weight, *e*, and *f f'* are stoppins arranged upon opposite sides of the cylinder in a line between the nozzle and vent-opening, and against which the bail strikes to prevent the cylinder from rotating too far in the operation of the device.

40 *g* is a ring attached to the side of the cylinder midway between the nozzle and vent-open-

ing, and to which is secured a cord, *g'*, as shown.

In the operation of the device the plug is removed and the reservoir filled with water. 55 The plug is replaced, and the can may be hung up by the bail in any convenient place ready for use. When not in use and filled with water the nozzle is turned upwardly, and will be held in that position by the weight *e* and the bearing of the pin *f* against the handle. By drawing upon the cord *g'* the cylinder will rotate upon its axis, carrying the nozzle downward and the weight *e* upward upon the opposite side. When the cylinder has revolved 60 until the nozzle has been carried to its lower or bottom side the pin *f'* will have reached the upper side and the weight *e* have passed the vertical line and have commenced to exert power to complete the revolution. This will 65 be prevented by the pin *f'*, which strikes against the bail and holds the cylinder in position with the nozzle downward. The water will then commence to run through the pipe and sprinkler, and the vent-pipe will allow the air to enter as the water flows out of the cylinder. 75

The advantages of this bath are that it is simple and economical of construction and convenient in operation.

What I claim is—

1. A portable bath consisting of a narrow cylinder, *A*, journaled centrally between the arms of the bail *a*, provided with a vent-pipe, *c*, arranged around its circumference, with feet *d d*, hook *g*, and tilt-cord *g'*, nozzle *a'*, in which 85 fits the plug *b*, provided with a flexible tube, *b'*, and sprinkler *b*², said pipe and sprinkler being adapted to convey the contents of the cylinder to the person who is to receive the bath, substantially as described.

2. In a portable bath, the combination of the cylinder *A*, provided with a vent-pipe, *c*, nozzle *a'*, plug *b*, pipe *b'*, and sprinkler, feet *d*, weight *e*, and pins *f f'*, with the bail *a*, all arranged substantially as shown and described. 95

In testimony whereof I affix my signature in presence of two witnesses.

THOMAS J. McCONNAUGHAY.
